UNITED STATES PATENT OFFICE.

JOHN J. MILNES, JR., OF PORT RICHMOND, NEW YORK.

MOLD-SUPPORT.

1,383,837.

Specification of Letters Patent.

Patented July 5, 1921.

Application filed July 16, 1920. Serial No. 396,691.

To all whom it may concern:

Be it known that I, JOHN J. MILNES, Jr., a citizen of the United States, and a resident of the city of New York, Port Richmond, in the 5 borough of Richmond, county of Richmond, and State of New York, have invented a new and Improved Mold-Support, of which the following is a full, clear, and exact description.

10 The present invention relates to new and useful improvements in concrete forms and it pertains more particularly to a bracket for supporting concrete forms in operative position.

15 It is one of the primary objects of the present invention to provide a device of this character especially adaptable for supporting forms to provide cappings for walls.

20 It is a further object of the invention to so construct the bracket that it is adjustable thereby adapting itself to forms of various sizes.

25 It is a still further object of the invention to provide a support for forms which is collapsible and capable of being knocked down to facilitate its transportation and storage.

With the above and other objects in view, reference is had to the accompanying drawings in which—

30 Figure 1 is a vertical sectional view of a portion of a wall showing the manner in which the present device is used;

Fig. 2 is a view in elevation of a wall showing an edge view of the bracket;

35 Fig. 3 is a detail perspective view of the bracket-securing means.

Referring more particularly to the drawings, the reference character 5 designates the wall and in the laying of the wall a wire 6' is embedded therein, the same being placed 40 at the desired point between two of the courses of bricks or blocks which form the wall. Adapted to be positioned on each side of the wall 5, is a member 6, in the form of a beam, and these members 6 are slotted as indicated by the reference character 7.

45 Secured to each of the members 6, as by means of rivets 8, are laterally projecting plates 9, and said plates 9 are each provided with elongated openings 10, said openings being parallel to each other.

50 Carried by the plates 9 are members 11, provided with elongated slots 12 for the reception of bolts 13. The bolts 13 are 55 adapted to pass through the elongated parallel slots 10 and receive a wing nut 14, by

means of which the members 11 are secured to the plates 9 in their adjusted position with respect thereto.

In Fig. 3 is shown a cam member 15, and said cam member 15 is provided near its cam end with openings 16, adapted for the reception of bolts 17. These bolts 17 are adapted to be received within the slots 7 to form the means by which the cam members 15 are pivotally secured to the members 6. The cam members 15 each have a handle portion 17', and between the handle portion 17' and the pivotal point 16, the cam members 15 are provided with openings 18 for the reception 65 of bolts 19, the purpose of which will be hereinafter described. A tongue 20 is provided on each of the cam members 15 and these tongues form the means by which the wire 6' heretofore mentioned, is secured to 70 the cam members.

The reference characters 25 and 26 designate the bottom and side boards, respectively, of the mold, and it is obvious from the adjustable relation between the members 11 80 and the plates 9, that within certain limits the dimensions of these bottom and side boards may be varied.

The device operates in the following manner:

Assuming that the wall 5 has been completed and the wire 6' has been placed between the desired courses with its ends protruding therefrom as shown in Fig. 1, and it is desired to build a capping on the top 90 of said wall—the members 6 are positioned on opposite sides of the wall as shown and the ends of the wire 6' are attached to the tongues 20 of the cam members 15, it being understood that the cam members are raised. 95 The cam members 15 are now rocked about their pivotal points 17 until sufficient strain is placed upon the wire 6' to retain the members 6 in place.

100 After the above described operation has been completed, the bottom boards 25 and the side boards 26 are positioned and the members 11 adjusted with respect to the plates 9 and secured in their adjusted position by means of the wing nuts 14. With the parts in this position, it will be seen that it is only necessary to fill in the concrete within the mold to provide the capping 27. After the capping or concrete has sufficiently 105 set to warrant the removal of the mold, this is done by merely rocking the cam members 15 to a position where the strain on the wire 110

6' is relieved, thus permitting the members 6 to fall away from the wall. The free ends of the wire 6' are now cut off, thus leaving the wall with its capping intact.

5. What is claimed is:

1. A support for capping molds comprising a plurality of standards adapted to be attached to a wall, means for securing said standards to said wall, plates projecting 10 angularly from said standards and adapted to support the mold, and means carried by the plates for maintaining the mold in operative position.

2. A support for capping molds comprising a plurality of standards adapted to be secured to opposite sides of a wall, cam means carried by the standards for securing them to the wall, plates projecting right- 15 angularly from each of said standards, said plates being provided with parallel elongated slots, and standards adjustably carried by said plates, said standards having elongated slots by means of which they are secured to the plates.

gated slots, and standards adjustably carried by said plates, said standards having elongated slots by means of which they are secured to the plates.

3. A device of the character described comprising a plurality of standards secured to opposite sides of a wall, plates projecting right-angularly from said standards at their upper ends and rigidly secured thereto, said plates having parallel elongated slots, standards provided with slots adapted to coincide with the slots of said right-angular plates, said last-mentioned standards serving to retain the mold in operative position, and means passing through the said coincident slots for securing the last-mentioned standards against movement relative to the right-angular plates, substantially as described.

JOHN J. MILNES, JR.
